UNITED STATES PATENT OFFICE.

WILLIAM W. STOUT, OF SOMERSET, INDIANA.

CEMENT FENCE-POST.

No. 874,453.

Specification of Letters Patent.

Patented Dec. 24, 1907.

Application filed August 13, 1907. Serial No. 388,393.

To all whom it may concern:

Be it known that I, WILLIAM W. STOUT, a citizen of the United States, residing at Somerset, in the county of Wabash and State of Indiana, have invented a certain new and useful Cement Fence-Post, of which the following is a specification, reference being had therein to the accompanying drawing.

This invention pertains to a new and useful fence-post; and the object thereof is to provide a cement post having peculiar designed fastening means for the line wires; these fastening means are formed of one piece of metallic wire, which is bent in the form of a loop, which is passed through any one of the apertures in the post, leaving the free end of the wire to be bent about the outer circumference of the post, so as to allow the ends thereof to be coiled about the line wires.

20 This invention comprises further objects and combinations of elements which will be hereinafter more fully described, shown in the accompanying drawings, and the novel features thereof will be pointed out by the appended claims.

To obtain a full and correct understanding of the details of construction, combinations of features, elements and advantages, reference is to be had to the hereinafter set forth 30 description and the accompanying drawings in connection therewith, wherein

Figure 1 is a perspective view of the improved fence-post embodying the features of the invention. Fig. 2 is a vertical section 35 through the fence-post. Fig. 3 is a cross sectional view on line 3—3 of Fig. 2. Fig. 4 is a detail view of the fastening means, for the line wires, detached from the post. Fig. 5 is a detail view of the loops 5, showing 40 the corrugations 10 which engage the line wires 8 to prevent longitudinal displacement thereof. Fig. 6 is a detail sectional view on line 6—6 of Fig. 5.

Making renewed reference to the accompanying drawings, wherein similar reference characters indicate corresponding parts in the several illustrations, 1 designates a fence-post, which is composed of cement, and embedded in which is a pair of metallic cores 11, as clearly shown in Fig. 3 of the drawings. The apertures 4, receive the loops 5 of the fastening means 6, which engage the line wires. The loops 5, are provided with a plu-

rality of serrations or corrugations 10, which prevent longitudinal displacement of the 55 line wires 8 as shown clearly in Figs. 1, 5 and 6. To form the said loops the fastening means consist of a single piece of wire, which is bent upon itself, as clearly shown, and the remaining portions of the said wires are bent 60 about the outer circumference of the cement post, so as to allow their extreme ends 7 to be coiled about the line wires 8, as clearly shown in Fig. 1. The metallic cores 11, are provided with a plurality of serrated portions 12, 65 which have a tendency to cause the cement to adhere to said cores, as clearly shown in Fig. 2.

It is to be understood that various changes and modifications may be employed in the 70 construction and embodiment thereof, combinations of features, and elements, without in any way departing from the spirit and scope of the invention covered by the claims thereof; it being understood that whatever 75 variations or modifications are employed must fall within the scope of the appended claims.

From the foregoing essential features, elements and the operation of the device, together with the simplicity thereof, will be clearly apparent.

Having thus fully described the invention, what is claimed as new and useful by the protection of Letters-Patent, is:—

In a fence post, composed of cement having transverse apertures, said posts having metallic cores provided with corrugations or serrations 12, fastening means for the line wires, comprising a single piece of wire bent 90 in its center and upon itself to form a loop, adapted to be inserted through said apertures, the said loop having a plurality of serrations to engage the line wires to prevent longitudinal displacement thereof, the portion of the wire beyond the loop surrounding the body of the post and having its ends coiled about the line wires, as and for the purpose specified.

In testimony whereof I hereunto affix my 100 signature in presence of two witnesses.

WILLIAM W. STOUT.
